UNITED STATES PATENT OFFICE.

EDWARD F. JONES, OF FARMINGTON, NEW HAMPSHIRE.

LAST.

SPECIFICATION forming part of Letters Patent No. 241,022, dated May 3, 1881.

Application filed January 18, 1881. (No model.)

To all whom it may concern:

Be it known that I, EDWARD F. JONES, of Farmington, of the county of Strafford, of the State of New Hampshire, have invented a new and useful Improvement in Shoe-Makers' Lasts; and I do hereby declare the same to be declared in the following specification, and represented in the accompanying drawings, of which—

10 Figures 1 and 2 are opposite side views, Fig. 3 a bottom view, Fig. 4 a longitudinal section, and Fig. 5 a transverse section, of a last provided with my invention. Fig. 6 is a perspective view of the combined metallic toe-guard and side re-enforces. Fig. 7 is herein-after described.

Wooden lasts are not only liable to crack lengthwise, but to become broken away at the edge of the sole, from the ball to the toe thereof, such being due to shrinkage or warping of the wood and to pegs and nails driven through the soles into the lasts.

Devices as hereinafter described are to prevent such injury to a wooden last, and in order therefor I provide the last A, or combine with it on its sides and at their junction with the sole two strips or re-enforces, B C, of metal, they being arranged as represented. In the drawings they are shown as in one piece 25 with and projecting back from a toe-guard, D, which is a metallic plate arranged with the toe and sole of a last in manner as represented, and fastened to the said last by screws *a a*, which go through the plate and screw into the 30 last.

To confine the side re-enforces to the last, I use rivets E, going entirely through the last and the two re-enforces, each of such rivets being screw-threaded throughout its shank, and screwed into the wood of the last, where there-in, in order for it, not only with the re-enforcers to prevent splitting or cracking of the last, but to accomplish this with additional effect by means of the screw-threads. 40

In Fig. 7 one of the screw-threaded rivets 45 is shown, it having its head nicked like an ordinary wood-screw, and its shank screw-threaded from head to end.

By having the re-enforcers attached to or in one piece with the toe-guard, they serve to mutually support each other on the last. 50

I do not claim a metallic toe-guard and side re-enforces or strips of metal made in separate pieces and fastened to a wooden last by screws going into but not through it. 55

What I claim as my invention is as follows, viz:

1. The wooden last provided with the metallic side re-enforces and their screw-threaded connecting-rivets passing entirely through the 60 last, arranged with such last as set forth.

2. The wooden last provided with the connected toe-guard and side re-enforces, and with the screw-threaded connecting-rivets, all arranged and applied substantially as set forth. 65

EDWARD F. JONES.
